UNITED STATES PATENT OFFICE.

WILLIAM S. WESTON, OF DALLAS, TEXAS.

ANTICREEPER FOR RAILWAY RAILS.

Application filed July 3, 1922. Serial No. 572,476.

To all whom it may concern:

Be it known that I, WILLIAM S. WESTON, a citizen of the United States, residing in the city of Dallas, county of Dallas, and 5 State of Texas, have invented certain new and useful Improvements in Anticreepers for Railway Rails, of which the following is a full, clear, and exact description.

My invention relates to improvements on 10 the V-form spring clamp anti-creeper set forth in U. S. Letters Patent No. 1,257,566 granted to me Feb. 26, 1918. The objects of my present invention are improvements in certain details of the construction of the 15 device, therein illustrated, described and claimed, which do not change the combination and relation of the several parts but which permit of a new and improved method of installation and a more perfect functional 20 operation. The full construction of the anti-creeper embodying these improved details, and the method of installation are hereinafter described and clearly illustrated in the accompanying drawings which form a 25 part of these specifications. The novel features are particularly pointed out in the claims.

In the drawings Fig. 1 is a side elevation 30 of a rail showing the anti-creeper in position against the tie. Fig. 2 is an elevation transverse to the rail as seen from the left of Fig. 1 with the tie omitted. Fig. 3 is a plan view of Fig. 1. Fig. 4 is an elevation transverse to the rail, similar to Fig. 2, with 35 the rail indicated by dotted outline, drawn to illustrate the manufactured shape and relation of the parts. Figs. 5, 6 and 7 illustrate the shape at different stages in the process of installation, the rail base in Fig. 5 being shown in dotted lines. Fig. 8 is a 40 plan view of the anti-creeper similar to Fig. 3, drawn to a larger scale to illustrate more clearly the lines of the three bearings against the rail base edges, the edges only 45 being shown by dotted outline. The same numerals of reference indicate the same parts in the several views.

Described in general terms my anti-creeper is a V-form spring clamp device, 50 made of resilient material, provided with three seats for bearing against the rail base edges, one seat at or adjacent the root of the V and one at or adjacent the free end of each arm or member. In the manufactured shape 55 the rail seating space between these three seats is less than required by the rail on which the device is to be used, and it therefore has to be sprung into position when being installed. The spring reaction establishes a friction grip on the rail at the three 60 seats, and because of this friction grip two of the seats on opposite edges of the rail base are established as the fulcrums of a lever grip which becomes effective in functional 65 operation. As stated my present invention has to do with improvements in details facilitating the installation and providing for a more perfect functional operation.

The anti-creeper is made preferably from a round rod of spring steel worked into exact shape in a forging or bending machine. Referring to Fig. 3 where it is seen in plan view the V-form has one arm or member, indicated by dotted outline and marked by the numeral 1, extending transversely beneath the rail and a second member 2 extending longitudinally adjacent the edge of one of the rail base flanges. The root of the V at 3 and the adjacent portion of the longitudinal member is offset upward from the center of the transverse member, as seen in Fig. 1, so as to form a shoulder seat 4 adapted to bear against one rail base edge, while the free end of the transverse member is bent upward at 5 to form a shoulder seat 6 adapted to bear against the opposite rail base edge. The distance between the seats 4 and 6 is somewhat greater than the width of the rail base so that when in operative position and bearing against the edges the transverse member will 70 lie at an angle with the rail slightly less than 90 degrees. The free end of the longitudinal member is inclined downward and made with sufficient length of stock to be 75 bent and formed into a special shape adapted to several purposes, as will be described, one of which is to provide a third seat 7 adapted to bear against the same rail base edge as the seat 4 at the root of the V. In forming the seat 7 the extra length of member 2 is first bent into a loop or eye 8 located beneath the rail base flange and adapted to 80 act as the tie abutting portion. The end of the stock is then bent upward past the edge of the rail base at 7^a and over the top at 7^b. The extreme end of the portion 7^b is curved or hooked backward on a line which if produced would extend above the transverse member. The upper portion of the loop 8, marked 7^c on the drawings, together with 85 the parts 7^a and 7^b form the three sides of a flange embracing jaw in the bottom of which 90

is located the seat 7 for bearing against the rail base edge.

Seat 7 is a jaw seat in the sense that the top and bottom portions 7^b and 7^c converging into the part 7^a form a tight fit at the edge of the rail base and provide against any vertical movement at the seat. Seats 4 and 6 are shoulder seats, as in conjunction with the transverse member they provide bearings on the bottom and edges only of the base flanges. With its top portion curved back as described the jaw seat by its connection to the transverse member through the medium of the loop and longitudinal member serves under normal conditions to hold the transverse member up against the base of the rail with the shoulders in operative position. The shoulder seat 6 on the free end of the transverse bar is provided preferably with a short nosing or projection 13 adapted to overhang the edge of the rail base flange. This nosing does not enter into the functional operation and its sole purpose is to provide against the seat working out of position under abnormal strains.

One of the prime features of improvement in my present invention will be found in the exact construction of the jaw seat as distinguished from the construction illustrated or described in my prior patent referred to. While the jaw is made with a tight fit right at the edge of the rail base the angle of convergence between the top and bottom parts 7^b and 7^c is greater than the angle of convergence between the top and bottom surfaces of the base flange. By this construction the jaw may have a rocking movement in a vertical plane transverse to the rail and about a center adjacent the lower fillet of the rail base edge. This movement, the range of which may be seen by comparing the position of the jaw in Fig. 2 with the position shown in Fig. 6, is provided for and utilized solely as an aid in the installation.

Fig. 4 illustrates the manufactured form to be such that, when the transverse bar with its seats 4 and 6 bearing against opposite base edges is in its operative position, the jaw seat 7 encroaches on the rail space and the top and bottom parts are rotated downward. Also the curved end of the top part is bent downward so that the space between this part and a surface represented by the base of the rail resting on the transverse member and in the juncture between parts 7^a and 7^c of the jaw is very much less than the thickness of the rail base flange. This contracted shape is necessarily expanded at installation and its contractile quality is depended upon to hold the device in operative position.

The installation process in which the jaw seat is rotated against the resilience of the loop 8 and the torsional resilience of the

longitudinal member 2, and thereby sprung outward relative to the transverse member, momentarily expanding the rail seating space beyond that required when finally seated, will now be described. The device is first placed by hand with the free end of the transverse member projecting under the rail and the jaw seat part way on one flange. It is then driven to the position of Fig. 7, and that of the dotted outline Fig. 5, by hammer blows applied adjacent the seats 7 and 4 as indicated by the arrows 9 and 10 in Fig. 5. In this position because of the contracted shape as manufactured the hook 5 with seat 6 and nosing 13 will not clear the rail base edge. Hammer blows are next applied to the end of the longitudinal member near its juncture with the loop as indicated by the arrow 16 in Figs. 6 and 7. These blows rock the jaw seat to the position of Fig. 6, contracting the loop 8 more or less at the same time, and carrying the adjacent end of the longitudinal member farther under the edge of the rail base. This action momentarily rotates the longitudinal member and the transverse member as a whole, about the bearing 4 at the root of the V for a center, from the position shown by dotted outline to the position shown by full outline in Fig. 5. In this momentary position the transverse member lies nearer at right angles to the rail so that the nosing 13 will clear the edge. During this last action as the nosing clears the edge the resilience in the shape brings the transverse member up against the base of the rail, while a further partial recovery of its manufactured shape following the last hammer blow brings the device to its installation position as shown in Figs. 1, 2, and 3.

It will be obvious that while I preferably use the rocking action of the jaw seat and the compression of the loop conjointly to accomplish the last movement of the installation just described, yet the compression of the loop alone by the blows at 16 might be utilized by making the loop larger and more yielding.

To further aid the installation process passing from the position of Fig. 7 to Fig. 6 and to make the hammer blows applied at 16 more or less cumulative I provide a short bevel 17 on the upper end of the hook 5 immediately above the nosing 13. As the blows are applied at 16 this bevel will work up on the lower fillet of the rail base edge because of the resilient reaction extending from the rocked jaw through the loop and longitudinal member to the transverse member.

In the functional operation the movement of the rail which tends to carry the device in the direction indicated by the arrow 14, Fig. 1, is met and held by the tie reacting in the opposite direction on the tie abutting the loop as indicated by the arrow 15. This

reaction thrust is transmitted to the rail through the longitudinal member, as indicated by the arrow 18, Fig. 8, to the root of the V at 3 and then to the rail through the leverage of the transverse bar with its shoulders 4 and 6 acting as fulcrums. As

5 stated at the beginning of these specifications the establishment of the lever grip is contingent on the establishment of a friction grip at all three seats or bearings on the rail base edges. This friction grip is a quality inherent in the device itself independent of functional operation and dependent upon the contractile quality of the shape. If the

10 tie reaction were transmitted through the device in such manner as not to utilize the lever grip the holding quality would be of small value. That this is so is disclosed by the fact that at the time of installation if 15 the device does not abut against the tie, as shown in Fig. 5, it may be set up to the tie by a light tap of a hammer at the root of the V in the direction of the arrow 19. In this action no lever grip is developed and 20 only the initial friction has to be overcome.

The development of a lever grip, which is 25 already provided for by the initial friction in the bearings, and a grip with a reliable holding quality, is a feature of fundamental importance in the operation of my device. The development of such a grip with the transverse member and its bearings acting in a horizontal plane is especially practicable and I therefore make this member and 30 its bearings as rigid and unyielding as possible and the bearings of such shape that they will take a reliable hold on the rail base edges. Referring to Fig. 8 the surfaces of 35 bearings 4 and 6 are slightly inclined to the edges of the rail base, the position of bearing 6 under the nosing being indicated by dotted line. This inclination permits the rear portions 4^a and 6^a to sink into the rust and scale on the base edges under the contractile reaction at the time of installation. The direction of the incline is such that in functional operation any tendency of the rail to move through the bearings in the direction indicated by the arrows 20, 20, would 40 cause the bearings to work deeper into the edges in much the same manner as a blunt nosed chisel. It may be noted that, while 45 I prefer to incline both bearing surfaces 4 and 6, a satisfactory operation can be had with only the surface 6 at the free end of the member inclined to the edge of the standard width of base with which it is to be used. This surface while made with a small angle 50 of incline is yet made with the angle large enough to have an incline in the same direction as illustrated even when the rail in actual use may be found to be rolled to a width of base slightly under the standard.

55 That the grip described is a genuine lever grip is clear from the fact that the tie re-

action thrust acting substantially parallel to the rail is transmitted to the transverse bar through the root of the V, at a point relatively outside, rather than between, the two fulcrums 4 and 6.

70 It is obvious that changes may be made in the proportions of the parts or in the kind of stock material from which the device is made without changing the character and combination of the parts essential to the installation and functional operations.

75 What I claim as new and desire to secure by Letters Patent is:—

1. A V-shaped anti-creep for railway rails, comprising a transverse member having shoulder seats adapted to grip the opposite rail base edges with a lever grip, and a longitudinal member having at its free end a tie-abutting portion terminating in a flange embracing jaw seat; said jaw seat being adapted to be rocked on one base edge transversely to the rail base flange in the process of installing the device and to hold the said shoulder seats in operative position after installation.

80 2. A V-shaped anti-creep for railway rails made of resilient material, comprising a transverse member having shoulder seats adapted to grip the opposite rail base edges with a lever grip, and a longitudinal member having at its free end a tie-abutting portion terminating in a flange embracing jaw seat; said jaw seat being adapted to hold the said shoulder seats in operative position, and said shoulder seats having inclined bearing surfaces adapted to chisel into the rail base edges in functional operation.

85 3. A V-shaped anti-creep for railway rails made of resilient material comprising a transverse member having two shoulder seats, one adjacent the root of the V and one at the free end thereof adapted to grip the opposite rail base edges with a lever grip, and a longitudinal member having at its free end a tie-abutting portion provided with a flange embracing jaw seat; said jaw seat being adapted to hold the shoulder seats in operative position, and said shoulder seat at the free end of said transverse member having an inclined bearing surface adapted to 100 chisel into the rail base edge in functional operation.

105 4. An anti-creeping device for railway rails comprising a spring clamp with three seats of bearing adapted to have a friction grip upon opposite edges of the rail base when sprung into position thereon, the bearing surfaces of two of said seats on opposite base edges being inclined thereto and adapted thereby to chisel into the said base edges 110 when moved thereon in functional operation.

115 5. An anti-creep for railway rails in the shape of a V-form spring clamp comprising: a transverse member having shoulder seats adapted to grip the opposite rail base edges 120

with a lever grip, one of said shoulder seats being located at the free end of said member and the other adjacent the root of said V-form; and a longitudinal member having at its free end a tie-abutting portion terminating in a flange-embracing jaw seat, said tie-abutting portion and said jaw seat being

adapted to permit at installation the momentary rotation of said transverse and longitudinal members in a horizontal plane about the said shoulder seat adjacent the root of the V-form. 10

WILLIAM S. WESTON.
